CLAIM

The ornamental design for a shoe upper, as shown and described.

DESCRIPTION

FIG. 1 is a first side view of a shoe upper showing my new design;

FIG. 2 is a first rear perspective view thereof;

FIG. 3 is a rear view thereof; and,

FIG. 4 is a second rear perspective view thereof.

The broken lines immediately adjacent to the shaded area define the bounds of the claimed design, and form no part thereof. The broken lines showing the remainder of the shoe are for environmental purposes only and form no part of the claimed design.
